(57) **CLAIM**

The ornamental design for an AR type buffer tube support bracket, as shown and described herein.

DESCRIPTION

FIG. 1 is a perspective view of the AR type buffer tube support bracket, showing my new design;

FIG. 2 is a bottom plain view thereof;

FIG. 3 is a top plain view thereof;

FIG. 4 is a side plain view thereof;

FIG. 5 is a rear plain view thereof; and,

FIG. 6 is a front plain view thereof.
